WASHING MACHINE

Percy E. Barker, Cleveland, Ohio, assignor to
Arthur Betz, Cleveland, Ohio

Application March 28, 1936, Serial No. 71,441

2 Claims. (Cl. 74—24)

My invention relates to washing machines of the pounder type, and the invention resides more particularly in the simple and effective mechanism herein shown and described for imparting reciprocal and rotary movements to the pounders; whereby the upward movement of the pounder may be accelerated and increased agitation of the water and improved washing effects may be obtained; whereby a straight line movement may be imparted by oscillatory means to the pounder shaft to avoid bind and wear on the shaft and its bearings; whereby the pounder shaft may be partially rotated by a ratchet device or its equivalent during the interval when the pounders are lifted to their highest elevation; and whereby adjustments may be conveniently made to vary the movements imparted by the said mechanism.

In the accompanying drawings:

Figure 1 is a side elevation and sectional view of a washing machine embodying my invention;

Figure 2 is a vertical section on a larger scale and at a different angle, of a tub and my improved pounder operating mechanism beneath the bottom thereof;

Figure 3 is a horizontal section of the operating mechanism on lines 3—3 and 3'—3' of Figure 2;

Figure 4 is a side view and section of the operating mechanism corresponding to Figure 2, but on a larger scale and with the parts shown in dotted lines in different working positions;

Figure 5 is a perspective view of the rocker arm;

Figure 6 is a perspective view of the crank connection;

Figure 7 is a perspective view of the supporting link for the rocker arm;

Figure 8 is a perspective view of the bracket from which the link is suspended;

Figure 9 is an enlarged section and top view on line 9—9 of Figure 10 device for rotating the pounder shaft; and

Figure 10 is a side view, partly in section, of the same device.

In power-operated washing machines of the pounder type it is a common practice to mount a rotatable and reciprocable shaft 2 centrally within a stationary tube 3 and provide a yoke 4 at the upper end of the shaft to carry cup-shaped pounders 5 within the tub. In the present instance the operating mechanism is located wholly beneath the bottom of the tub and comprises an electric motor 6 suitably suspended from a supporting frame 7 for the tub and operatively connected by a friction clutch 8 and with a train of speed-reducing gearing 9 mounted within a suitable casing 9' which is also suspended from

frame 7, see Figure 1. When a wringer 10 is mounted upon the tub it may be operated by the same gearing 9, and a suitable clutch 11 may also be used, see Figure 3, to transmit power by means of a separate shaft 12 and a crank 14 to the operating mechanism for the pounder shaft 2. Thus, referring to Figures 2 and 4, a link 15 connects the crank pin pivotally with a bent lever or rocker arm 16 which is pivotally supported at its outer end upon the lower forked end of a short link 17. The upper forked end of link 17 is suspended from a hinge pin 18 extending through an ear 19 on a depending bracket 20, thus permitting the link and rocker arm to swing back and forth within limits in respect to pounder shaft 2 when said arm is oscillated vertically by crank 14 and connecting link 15. A coiled compression spring 21 is interposed between the top 5 of bracket 20 and a lateral branch 22 on swinging link 17 to hold the link yieldingly against the vertical leg of the bracket, or against the end of an adjustable stop, such as a set screw 24. Bracket 20 is formed with a straight vertical rib 25 which is co-extensive with the swinging link and projected a given distance beyond the inner end of set screw 24 to permit a curved wing or 10 cam rib 26 on the bottom of rocker arm 16 to engage and rock on the flat face of rib 25 during a part of the time that said rocker arm is oscillated by crank 14. A shoe 27 of U-shape is pivotally 15 connected with the bifurcated end 28 of rocker arm 16 and this shoe is free to slide and reciprocate between a fixed collar 29 and an oscillating collar 30 mounted upon the lower end of pounder shaft 2. Thus during the oscillatory movements 20 of rocker arm 16 the pounder shaft 2 is reciprocated and also rotated by shoe 27, the rotary movement being effected intermittently by a ratchet wheel 31 and a spring pressed ball 32 or 25 its equivalent, carried by collar 30. As shown, ball 32 is held within an offset 33 at one side of loose collar 30 opposite the ratchet teeth, and a pin 34 extends upwardly from one leg of the U-shaped shoe into a radial slot 35 in collar 30. The ratchet wheel is pinned to pounder shaft 2 30 and collar 30 is free to rotate in respect thereto, thereby permitting the reciprocable movement of the shoe to oscillate collar 30. The idle stroke of the ratchet wheel occurs when the rocker arm moves the pounder shaft downwardly, and the working stroke of the ratchet wheel and turning of the pounder shaft takes place during the latter part of the upward movement of the rocker arm and shaft, that is, while the pounders are emerging 35 from the water in the tub. The upward 40 movement of the pounder shaft is effected by the 45 rotation of the ratchet wheel and the upward movement of the shoe 27. The upward movement of the shoe 27 is effected by the upward movement of the 50 rocker arm 16, the upward movement of the rocker arm 16 being effected by the upward movement of the 55 link 15, the upward movement of the link 15 being effected by the upward movement of the crank 14, the upward movement of the crank 14 being effected by the upward movement of the shaft 12, the upward movement of the shaft 12 being effected by the upward movement of the gear 9, the upward movement of the gear 9 being effected by the upward movement of the motor 6, the upward movement of the motor 6 being effected by the upward movement of the frame 7, the upward movement of the frame 7 being effected by the upward movement of the tub 3, the upward movement of the tub 3 being effected by the upward movement of the water in the tub 3.

movement is more rapid than the downward movement, and the shoe carrying end of the rocker arm moves partly in an arc to reciprocate the shoe horizontally, and partly in a straight line 5 to reciprocate the pounder shaft vertically without side thrust, especially when the shaft is projected a substantial distance downwardly beyond its bearing 36. Thus, assuming pounder shaft 2 to be in its highest position as shown in full 10 lines in Figure 4 the rotation of crank 14 in the direction of arrow X on an arc of approximately one hundred and twenty degrees will swing the free end of the rocker arm downwardly because the fulcrum of movement of the rocker arm is 15 definitely fixed at this time by set screw 24 which serves to limit the outward movement of supporting link 17 under the pressure of coiled spring 21. Then as crank 14 continues to rotate, say ninety degrees additionally, the heel 37 of the cam or 20 rocker 26 on arm 16 engages rib 25 on bracket 26 and a rocking movement is imparted to arm 16 which causes the shoe carrying end of the arm to move downwardly on a straight line parallel with the longitudinal axis of pounder shaft 2 until the 25 limits of its downward stroke is reached. Supporting link 17 swings toward pounder shaft 2 during the straight line rocking movement just described and compresses spring 21, but as crank 14 continues to rotate about sixty degrees further 30 the said spring will reverse the swinging movement of supporting link 17 toward set screw 24 thereby keeping the cam rib 26 in riding engagement with 25 as the rocker arm is raised approximately halfway by the crank and connecting link 35 14. Thus shoe 27 is caused to rise on a straight line for a given distance before it is shifted horizontally to rotate loose collar 30 and ratchet wheel 31, the latter movement being brought about during the last ninety degrees movement of 40 crank 14 when supporting link 17 is in a rest position against stop screw 24 and the rocker arm is moving upwardly in an arc to its highest position and place of beginning as illustrated in full lines in Figure 4. The combined swinging and

rocking movement of rocker arm 16 is desirable for several reasons; it promotes a smooth and silent application of power; it permits a straight longitudinal thrust to be imparted to the pounder shaft when the said shaft is projected its greatest 5 distance from its being; it permits a rotative movement to the pounder shaft during that part of its stroke when the plungers are being lifted out of the water or out of contact with the goods in the tub; it permits the pounders to be raised 10 more rapidly than they are caused to descend, the downward movement taking place through approximately two hundred and ten degrees of revolution of the crank and the upward movement requiring only one hundred and fifty degrees or 15 thereabouts to complete the cycle of movement of the crank; and it permits the use of a spring to aid the crank and motor in raising the pounders and overcoming the suction effect in washing operations. 20

Having thus described my invention what I claim is:

1. Power operating mechanism suitable for a washing machine of the type described, comprising a reciprocable and rotatable shaft having a 25 ratchet clutch connected therewith, an oscillatory arm having an operating member for said clutch, a crank having a link connected with said arm, a bracket having a link supporting one end of said arm, and a spring and rocker to change the work- 30 ing position of the arm in respect to the crank.

2. A power mechanism for the purpose described, comprising a reciprocating shaft, an oscillating arm having a loose connection at one end with said shaft, a crank having a link connection 35 with said oscillating arm intermediate its ends, a link supporting the opposite end of said arm, a cam for limiting the movement of the arm in one direction, and a spring controlling the supporting link whereby the position of the working arm is 40 changed in respect to the crank to accelerate the movement of the shaft in one direction.

PERCY E. BARKER.
